DRY SHAVER

Charles Caise, Brooklyn, N. Y.

Application February 8, 1937, Serial No. 124,730

16 Claims. (CL. 30—43)

My invention relates to the art of safety razors and more particularly to those known as dry shavers.

Primarily the invention has for an object to provide a dry shave razor of a simple, inexpensive construction by the use of which a close shave may be had without danger of cutting oneself.

Further, it is an object to provide a motor driven razor the cutting edge of the blade of which is held parallel to the skin and outer contour of the razor, a position in which the razor cannot chafe the skin.

Further, it is an object to provide a razor of the type stated in which the cutting edge of the blade is prevented from injuring the skin by means of a very fine non-corrosive wire grating substantially paralleling the cutting edge of the blade and extending at right angles to the same.

Other objects will in part be obvious and in part be hereinafter set forth.

To the attainment of the aforesaid objects and ends the invention further resides in those novel features of construction, combination and arrangement of parts which will be hereinafter first fully described and then specifically pointed out in the appended claims, reference being had to the accompanying drawing in which

Fig. 1 is a magnified view in front elevation of a razor embodying the invention, parts being broken away.

Fig. 2 is a vertical section on the line 2—2 of Fig. 1.

Fig. 3 is a section on the line 3—3 of Fig. 2. Fig. 4 is a top plan view, the cover being removed.

Fig. 5 is a perspective view on a reduced scale of the blade carrier.

Fig. 6 is a top plan view, on a reduced scale, of the guard plate head.

In the drawing in which like numbers of reference indicate like parts in all the figures, 1 represents the handle in which a suitable electric rotary motor (not shown) drives a shaft 3 having an eccentric pin 4. The handle 1 is threaded at 2 to receive the threaded end of the tubular shank 5 in whose hollow 6 the blade moving arm 25 is located. The arm 25 has a concentric recess to receive the eccentric pin 4 whereby rotation of shaft 3 imparts a rotary motion to the lower end of arm 25. The shank 5 carries the guard plate head 7 which on its front and back sides is provided with trough like passages 8 containing grating bars 9 spaced relatively a substantial distance apart. The head

7 has a pocket 10 in its top and is provided with blade guide surfaces 11 over which the thin flexible wafer blade 30 projects.

The side ends 12 of the head 7 extend upwardly a suitable distance to support the cover 15. 5

Slots 13 in the head 7 serve to receive the wings 26 depending from the underside of the blade carrier plate 24.

The cover 15 includes very fine wire gratings 17 and turned under portions 16 the former extending over the openings 8 while the latter clip around the edges 14 of the head 7 (see Figs. 1 and 2).

The cover 15 is held in place by any suitable means, as for instance spring fingers 18 and 15 lugs 19.

The blade carrier plate 24 has the arm 25 hereinbefore referred to and also the wings 26, the latter having pivot bearing holes 27 to receive the bearing portions 28 of pivot pins screwed at 29 into the ends 12 of the head 7.

The blade 30 may be of the well known wafer type (Gillette, Probak, etc.) and is slotted to fit over the rib or protuberance 22. The blade is held down, in its bowed shape, on the plate 24 25 by means of a blade pressing cap plate 20 (also slotted at 21 to fit over the member 22) and screws and washers 23 or in any other suitable way.

The shapes of the various parts are so designed 30 that the cutting edges of the blade will lie approximately parallel to the gratings 17 during their cutting movements, and close to those gratings 17.

The razor is used in the same way as the well 35 known Gillette razor.

The rotary motion of shaft 3 is converted into motion in the direction of the two arrows *a* and *b* in Fig. 4, i. e., a left and right movement (effecting a draw cut) and a front and back movement (effecting a chopping cut); the front and back movement of the blade is very slight in practice, about one-sixteenth of an inch or so, due to the leverage between pivotal axis 28—28 40 and the top and bottom of the member 25, while the movement above such axis is considerably less (about half as much).

Since the wires 17 may be made exceedingly thin, say one-sixty-fourth of an inch, and are spaced apart a fraction more than the thickness 50 of a hair, all danger of pressing the skin "through the bars" is avoided and hence a close shave can be had without cutting the skin.

From the foregoing description, taken in connection with the accompanying drawing, it is 55

thought that the construction, operation and advantages of the invention will be clear to those skilled in the art.

While I have herein described the preferred embodiment of the invention, it should be understood that changes in the details of construction and form of the parts may be made without departing from the scope of the invention as recited in the appended claims.

10. What I claim is:

1. In a dry shaver, a guard plate head having a tubular shank, a blade carrier, a wafer blade carried by said carrier and having a cutting edge, means pivotally mounting said carrier on an axis parallel to the cutting edge of the blade, said blade carrier including an arm located in said shank and a carrier plate located over said guard plate head, means for rocking said blade carrier on its pivot and reciprocating it along its pivot axis, and a cover mounted on said guard plate over said pocket.

2. In a dry shaver, a guard plate head having a tubular shank, a blade carrier, a wafer blade carried by said carrier and having a cutting edge, means pivotally mounting said carrier on an axis parallel to the cutting edge of the blade, said blade carrier including an arm located in said shank and a carrier plate located over said guard plate head, means for rocking said blade carrier on its pivot and reciprocating it along its pivot axis, a cover mounted on said guard plate over said pocket, and a grid over the cutting edges of the blade.

3. In a dry shaver, a guard plate head having a tubular shank, a blade carrier, a wafer blade carried by said carrier and having a cutting edge, means pivotally mounting said carrier on an axis parallel to the cutting edge of the blade, said blade carrier including an arm located in said shank and a carrier plate located over said guard plate head, means for rocking said blade carrier on its pivot and reciprocating it along its pivot axis, a cover mounted on said guard plate over said pocket, said blade having two parallel cutting edges, and grids over said cutting edges, said guard plate having hair discharge openings below said cutting edges.

4. In a dry shaver, a guard plate head of spread U-shape in end view having a tubular shank, and having blade guide surfaces, a blade carrier having a blade carrier plate located over said guard plate head and having an arm projecting into said tubular shank, a handle to which said shank is attached, a rotary shaft in the handle having a cam or eccentric-like connection with said arm, and means to mount said blade carrier on said guard plate head for movement back and forth in two paths at right angles to one another, and a thin wafer blade secured to said blade carrier and shaped so that the cutting edges of the blade will lie substantially parallel with the face when the instrument is in operation.

5. In a dry shaver, a guard plate head of spread U-shape in end view having a tubular shank, and having blade guide surfaces, a blade carrier having a blade carrier plate located over said guard plate head and having an arm projecting into said tubular shank, a handle to which said shank is attached, a rotary shaft in the handle having a cam or eccentric-like connection with said arm, means to mount said blade carrier on said guard plate head for movement back and forth in two paths at right angles to one another, a thin wafer blade secured to said blade

carrier and shaped so that the cutting edges of the blade will lie substantially parallel with the face when the instrument is in operation, and a protecting cap on said head over the blade and its carrier.

6. In a dry shaver, in combination, a guard plate head having a shank, a blade carrier mounted on said head, a wafer blade having a cutting edge and carried by said carrier, and means to oscillate said carrier and blade on an axis parallel to said cutting edge and reciprocate the same along said axis.

7. In a dry shaver, in combination, a guard plate head, a blade carrier, a wafer blade having a cutting edge and being carried by said carrier, means to mount said carrier on said head to turn on an axis located parallel to said cutting edge and for movement along said axis rectilinearly, and means to effect simultaneous oscillation of said carrier about said axis and reciprocation of said carrier along said axis, thereby to impart a combined draw cut and chop cut to said blade.

8. In a dry shaver, a guard plate head, a blade carrier, a wafer blade having two parallel cutting edges and being carried by said carrier, a cover plate mounted over said carrier and blade and having provisions to leave the cutting edges of said blade exposed for action, means to mount said carrier on said head to turn on an axis parallel to said cutting edges and for movement along said axis, and means to effect oscillation of said carrier about said axis and to reciprocate said carrier along said axis.

9. In a dry shaver, a guard plate head having a shank, a blade carrier mounted on said head, a wafer blade carried by said carrier, means to impart a combined draw cut and chop cut to said blade, said means comprising a rotary shaft, an arm carried by said blade carrier within a space in said shank, an eccentric connection between said shaft and said arm in virtue of which rotary motion of the shaft will be imparted to said arm, and means to mount said blade carrier in virtue of which the blade will be given an orbital movement.

10. In a dry shaver, a guard plate head having a shank, a blade carrier mounted on said head, a wafer blade carried by said carrier, means to impart a combined draw cut and chop cut to said blade, said means comprising a rotary shaft, an arm carried by said blade carrier within a space in said shank, an eccentric connection between said shaft and said arm in virtue of which rotary motion of the shaft will be imparted to said arm, and means to mount said blade carrier in virtue of which the blade will be given a back and forth movement along two paths, one in a direction transverse of the other.

11. In a dry shaver, a guard plate head having a shank, a blade carrier mounted on said head, a wafer blade carried by said carrier, means to impart a combined draw cut and chop cut to said blade, said means comprising a rotary shaft, an arm carried by said blade carrier within a space in said shank, an eccentric connection between said shaft and said arm in virtue of which rotary motion of the shaft will be imparted to said arm, and means to mount said blade carrier in virtue of which the blade will be given a reciprocating movement along an axis and an oscillating movement on said axis as a pivot.

12. In a dry shaver, a guard plate head of spread inverted U-shape in end elevation and

- having a tubular shank beneath and a pocket in its upper face, said head having passages for cut hair to fall through, a razor blade carrier mounted in the pocket of said head and having an arm located in said tubular shank, a blade on said carrier, and means for imparting to said blade carrier a combined oscillating motion around an axis and a reciprocating motion along said axis.
- 5 13. In a dry shaver, a guard plate head of spread inverted U-shape in end elevation and having a tubular shank beneath and a pocket in its upper face, said head having passages for cut hair to fall through, a razor blade carrier mounted in the pocket of said head and having an arm located in said tubular shank, a blade on said carrier, and means for imparting to said blade carrier a combined oscillating motion around an axis and a reciprocating motion along 10 said axis, said blade comprising a wafer having parallel cutting edges projecting partly across said passages.
- 10 14. In a dry shaver, a guard plate head of spread inverted U-shape in end elevation and having a tubular shank beneath and a pocket in its upper face, said head having passages for cut hair to fall through, a razor blade carrier mounted in the pocket of said head and having an arm located in said tubular shank, a blade on 15 said carrier, means for imparting to said blade carrier a combined oscillating motion around an axis and a reciprocating motion along said axis, said blade comprising a wafer having parallel cutting edges projecting partly across said passages, and fine grids over said blade edges and said passages, said grids lying approximately parallel to and adjacent the face of the blade at the cutting edges.
- 15 16. In a dry shaver, the combination with a 20 guard plate head having a shank, a blade carrier, a wafer blade having a cutting edge and carried by said carrier, of means to mount said carrier removably on said head and means to move said blade carrier bodily simultaneously in 25 two directions, one direction being parallel to the edge of the blade to produce a draw cut and the other direction being at right angles to the edge of the blade to produce a chop cut, thereby giving a combined draw cut and chop cut movement to the blade.
- 20 25 30

CHARLES CAISE.
